CLAIM

The ornamental design for an ice skate blade bending apparatus, as shown and described.

DESCRIPTION

FIG. 1 is a perspective view of an ice skate blade bending apparatus.

FIG. 2 is an exploded front perspective view thereof.

FIG. 3 is a front view thereof.

FIG. 4 is a front perspective view thereof.

FIG. 5 is another front perspective view thereof; with the lever arm in an alternate position.

FIG. 6 is a rear perspective view thereof.

FIG. 7 is a rear view thereof.

FIG. 8 is another rear perspective view thereof.

FIG. 9 is a top view thereof.

FIG. 10 is a side view thereof; and,

FIG. 11 is the other side view thereof.

The broken lines showing parts of a speed skate blade are for the purposes of showing environmental structure and form no part of the claimed design.

1 Claim, 7 Drawing Sheets
